DESIGN FOR PAJAMAS

Jacques E. Abraham, New York, N. Y.

Application December 4, 1937, Serial No. 73,350

Term of patent 3½ years

To all whom it may concern:

Be it known that I, Jacques E. Abraham, a citizen of the United States of America, residing in New York city, in the Borough of Manhattan, county and State of New York, have invented a new, original, and ornamental Design for Pajamas, of which the following is a specification, reference being had to the accompanying drawing, forming part thereof, wherein,

The design is characterized by the quilted floral elements in combination with the pajamas as shown.

I claim:

The ornamental design for pajamas, substantially as shown, and described.

JACQUES E. ABRAHAM.
